UNITED STATES PATENT OFFICE

HENRY A. BARBER, OF WATERTOWN, NEW YORK.

EXHAUSTING THE AIR, GASES, AND WATER FROM SUCTION-BOXES FOR PAPER-MAKING MACHINES.

SPECIFICATION forming part of Letters Patent No. 280,555, dated July 3, 1883.

Application filed March 21, 1883. (No model.)

To all whom it may concern:

Be it known that I, HENRY A. BARBER, of Watertown, in the county of Jefferson and State of New York, have invented certain new and useful Improvements in Exhausting the Air, Gases, and Water from Suction-Boxes for Paper-Making Machines; and I do hereby declare the following to be a full, clear, and exact description of the invention, such as will enable others skilled in the art to which it pertains to make and use it, reference being had to the accompanying drawings, which form part of this specification.

My invention relates to an improvement in exhausting the air, gases, and water from suction-boxes of paper-making machines, to be used in connection with paper and other machines where it is desired to exhaust the water from felts and pulpy material; and it consists in the combination of one or more draft-tubes which are connected with a reservoir of water, a connecting pipe or pipes, and a box having a perforated cover or open top, over which the paper, pulp, or other material is moved in a continuous sheet or mass, as will be more fully described hereinafter.

The object of my invention is to form a more perfect exhaust or vacuum when operating upon pulpy fluids containing a large amount of air or gases, so as to give a much steadier and more reliable suction than can be obtained with siphons of ordinary construction, or pumps as ordinarily used in connection with paper, felt, or other pulp machines of any kind.

Figures 1 and 2 represent side elevations of my invention, taken from opposite sides. Fig. 3 is an end view of the same. Fig. 4 is a plan view. Fig. 5 is a side elevation of my invention, showing the relative position of the parts when in use.

C represents a reservoir or water-supply chamber of any suitable shape, size, or construction which may be preferred, and which is connected to any suitable water-supply so as to always maintain about the same elevation. Secured to or placed at one end of this reservoir C is a much shallower box or chamber, G, which is to be filled with water or any other fluid which will form a seal for the lower ends of the two draft-tubes A E. In actual

operation the lower ends of these pipes will be sealed in a stream of running water. The shorter one, A, of the two draft-tubes is connected to the reservoir, near its top, by the pipe B, which extends a suitable distance downward into the reservoir, and by a second pipe, H, at any suitable distance below the lower end of the pipe B, and which pipe H is provided with a stop-cock, valve, or other shut-off, L, so that the flow of the water through the pipe H can be controlled and regulated at will. The longer one, E, of the two draft-tubes is connected with the draft-tube A by means of the pipe T, which extends from the top of the tube A up near the top of the tube E. Also connected with the top of the tube E is the pipe F, which extends any suitable distance down into the reservoir C. Although only two draft-pipes, A E, are here shown, there may be a larger number, if so preferred. The draft-tube E should in no case extend from above the level of the water in the reservoir C to a greater height than the fall from surface of water in reservoir C to the surface of water in G. One or more tubes may be used extending up about thirty feet, or near the limit of a perfect vacuum.

Extending from the top of the draft-tube E is a pipe, N, which has its other end connected with the tube of the separating-chamber M, which can be placed in an adjoining room or at any desired distance from the reservoir, and of the same level or at a higher or lower point than the draft tube or tubes. This separating-chamber is here shown as placed above the top of the reservoir merely as a matter of convenience and not as a matter of necessity.

Leading from the side of the separating-chamber M is a pipe, P, which has its other end connected with the box O, one only being shown, which has a perforated cover, and over which the endless wire cloth, or screen, or felt carrying a moist sheet of paper-pulp is caused to pass, as used on a Fourdrinier or other paper-making machine. From the bottom of the separating-chamber M extends a pipe, R, which has its lower end immersed in water or other sealing medium contained in the box S. The term "separating" is applied to the chamber M, because in this chamber the water, air, and gas are separated, the air and gas being

drawn off through the pipe N into the tops of the draft-tubes A E, while the water and heavier portions mixed therewith flow off through the pipe R.

5 When desirable, separating-chamber M can be located on a level sufficiently above the perforated box O, and cause said chamber to discharge water out about the same level with box O, through pipe R, which, with box S, is 10 raised, care being taken to have pipe R of same length as used to discharge on lower level. As the water which is drawn from the paper or pulpy material often contains some of the material itself, or coloring-matter, or chemicals of some kind, it is desirable to catch this water and save it, and it is therefore separated in the chamber M.

The operation of my invention is as follows: The lower ends of the two draft-tubes A E 20 are immersed in the water in the box G, so as to seal their ends, and thus prevent air and gas working up the draft-tubes, and thus insuring against risk of losing any part of the vacuum through that source. The gate or 25 stop-cock L in the pipe H being opened, a flow of water is started through the pipe A, and this water flowing through the pipe A will carry with it enough of the air and gas contained in the pipe A and start a flow of 30 water through the pipe B into the top of the tube A. The flow of water from this pipe B will still further cause the air and gas in the pipe A to be entrained with the water, and thus forced out of the pipe, causing as near a perfect 35 vacuum in the pipe as possible. This pipe A, being connected by the pipe T with the second draft-tube, E, the air and gas contained in the pipe E are drawn out into the pipe A until a sufficient vacuum has been 40 formed in the pipe E to start a siphonic flow through the pipe F into the top of the draft-tube E. The vacuum in the two pipes A E, caused by the downward flow of the water, will cause the gas and air to be exhausted from 45 the separating-chamber M, and the vacuum or partial vacuum formed in this chamber M will be exerted through the pipe P and the perforated cover of the box O upon the sheet of wet paper, pulp, or other material which 50 is being passed over the top of the box O.

Where it is desired to save the water for the purpose of using it over again, the separating-chamber will be used; but where it is not desirable to use the water over again, this 55 separating-chamber will be entirely done away with, and the connecting-pipe will then extend directly from the suction-box to the suction-tubes. It will be seen that this separating-chamber may or may not be used.

60 I am aware that a pipe has been connected to the bottom of a suction-box, and steam or water forced through the pipe; but this device is dependent entirely for its action upon the amount of air which will be drawn in by the current. My invention differs from this in connecting one end of a pipe with the suction-

box, and the other to a stand-pipe through which a great suction is caused by the fall of a large body of water. In the one case only a slight and indirect suction is caused, while 70 in the latter a positive and direct suction is caused.

I am also aware that pipes provided with cocks have been connected with the suction-box, so that when the cocks are opened the 75 water will flow freely out. My invention differs from this in connecting the reservoir with a stand-pipe by a short pipe provided with a cock, whereby when the cock is opened the water flows into the stand-pipe and starts the 80 whole machine into operation. In neither of the above-mentioned cases are stand-pipes employed, while the whole operation of my invention depends on them.

Having thus described my invention, I 85 claim—

1. The combination of one or more draft-tubes, A E, connected by a suitable pipe or pipes with the reservoir of water, and a perforated or open box, O, over which a sheet of 90 moist paper, pulp, or other material is made to pass, substantially as shown.

2. The combination of one or more draft-tubes, A E, having their lower ends submerged in a sealing medium, with suitable pipes by 95 which they are connected with the reservoir, and a separating-chamber, M, which is connected with a perforated or open box, O, substantially as described.

3. The combination of one or more draft-tubes, A E, connected by suitable pipes with the reservoir, the separating-chamber M and pipes N, P, R, and a perforated or open box, O, substantially as set forth.

4. The combination of the separating-chamber, the pipe P for connecting it with a perforated or open box, and the pipe R, having its lower end immersed in a sealing medium, whereby the air and water are withdrawn from the paper, pulp, or other material by the vacuum created in the chamber, and caused to separate, substantially as specified.

5. The combination of a reservoir, a draft-tube, A, having the siphonic tube B, connected with its upper end, and a tube, H, provided 115 with a gate or stop-cock connecting the draft-tube with the reservoir C, whereby the flow of water can be started through the tube B, substantially as shown and described.

6. The combination of the suction-box of a 120 paper-machine with a connecting-tube and one or more draft-tubes which are connected directly thereto, so that the draft-tubes will exert a direct suction upon the box, substantially as shown and described.

In testimony whereof I affix my signature in presence of two witnesses.

HENRY ANSEL BARBER.
